UNITED STATES PATENT OFFICE.

ALFRED H. HUMPHREY, OF KALAMAZOO, MICHIGAN.

DESIGN FOR A GAS-LAMP.

SPECIFICATION forming part of Design No. 35,481, dated December 24, 1901.

Application filed January 21, 1901. Serial No. 44,222. Term of patent 7 years.

To all whom it may concern:

Be it known that I, ALFRED H. HUMPHREY, a citizen of the United States, residing at the city of Kalamazoo, in the county of Kalamazoo and State of Michigan, have invented and produced a certain new and useful Design for a Gas-Lamp, of which the following is a specification.

This invention relates to a design for gas-lamps known as "cluster lights."

The design is fully illustrated in the accompanying drawings, forming a part of this specification, in which—

Figure 1 is a detail perspective view of a gas-lamp embodying the features of my design. Fig. 2 is an inverted plan view of the same.

As shown in the drawings, the leading or material features of my design consist of the central pipe A, from which, near its lower end, project radial arms or branches B. On the ends of these branches or arms are rounded or globular-shaped portions b, from the under side of which project the stems b'. Extending upwardly from the upper side of said portions b of the arms or branches B are tubes C, which have spiral corrugations. On the

upper end of these tubes C are the portions D, with mantles E thereon. Above the branches or arms B a stem a projects from the pipe A. 30 This stem a has a cross-stem a' a'. Projecting from the central pipe A at a point above the arms or branches B is another branch or arm F. On the end of this branch or arm F and substantially at right angles thereto is 35 an upwardly-extending tubular portion F', from the lower end of which projects the stem f. Outwardly and upwardly curved supports G project from near the bottom of the central portion A. On the upper ends of said 40 curved supports is an ornamental band H, on which is a globe, as I. On the top of the globe is a second ornamental band, as H'.

Having thus described my invention, what I claim as new, and desire to secure by Letters 45 Patent, is—

The design for a gas-lamp, as herein shown and described.

In witness whereof I have hereunto set my hand and seal in the presence of two witnesses. 50

ALFRED H. HUMPHREY. [L. S.]
